(57) **CLAIM**

The ornamental design for a sponge brush, as shown and described.

DESCRIPTIONFIG. 1 is a top perspective view of a sponge brush;
FIG. 2 is a bottom perspective view of the sponge brush, as shown in FIG. 1;

FIG. 3 is a top plan view of the sponge brush, as shown in FIG. 1;

FIG. 4 is a side elevation view of the sponge brush, having left-right symmetry, as shown in FIG. 1;

FIG. 5 is a bottom plan view of the sponge brush as shown in FIG. 1;

FIG. 6 is an end elevation view of the sponge brush, having front-rear symmetry, as shown in FIG. 1; and,

FIG. 7 is cross-sectional, end elevation view of the sponge brush along the line 7 of FIG. 5 and as shown in FIG. 1. The dashed line shown is provided for cross-sectional purposes only and form no part of the claimed design.
